UNITED STATES PATENT OFFICE.

JOHN FOWLER, OF CHICAGO, ILLINOIS.

BRIDGE-GATE.

No. 808,531.

Specification of Letters Patent.

Patented Dec. 26, 1905.

Application filed November 21, 1904. Serial No. 233,780.

To all whom it may concern:

Be it known that I, JOHN FOWLER, a citizen of the United States, residing at Chicago, in the county of Cook and State of Illinois, 5 have invented a new and useful Bridge-Gate, of which the following is a specification.

My invention relates to bridge-gates which move in vertical guides located on the bridge approaches; and the objects of my improvements are, first, to have the gates operated automatically by the turning of the bridge; second, to provide a continuous positive connection between the gates and the bridge; third, to facilitate the easy and rapid adjustment of the connections between the gates and the bridge; fourth, to provide a simple, cheap, and durable construction, and other objects to become apparent from the description to follow.

Heretofore bridge-gates have been made wherein the gates were automatically opened and closed by the turning of the bridge; but the construction and connection of the parts were so complicated and difficult to adjust 20 that they were considered impractical. Furthermore, the presence of numerous gear-wheels or levers which were required caused the whole apparatus to be moved with difficulty. These objectionable features are all 25 overcome by the use of my invention, which consists of providing a vertically-moving gate on each approach which is counterweighted to just barely drop down or shut by gravity and connected by a cable to the bridge in such manner that the gates are up 30 or open when the bridge is closed or open for traffic and are down or closed when the bridge is open or closed for traffic.

To better describe my invention, I have 40 illustrated the same in the two accompanying sheets of drawings, forming a part of this specification, in which—

Figure 1 is a plan view of a bridge and gates embodying my invention. Fig. 2 is a section taken on line 2-2 of Fig. 1. Fig. 3 is an elevation of one of the abutments, showing a portion of the gate structure in section; and Fig. 4 is a detail section of the cable-fastening.

Similar reference characters refer to similar 50 parts throughout the several views.

The bridge 5 is arranged to pivot about in the center on a center pier 6 in the usual manner and may be operated by manual or steam power.

55 The bridge-abutments 7 are provided with the usual step or offset 8, and the idlers 9 on

the ends of the bridge engage the track 10 when the bridge is shut or open for traffic. The construction thus far described does not embody any part of my invention and may 60 be of any construction whatever.

A suitable distance from the bridge on the abutment 7 are erected two preferably hollow posts 11, one on either side of the roadway, connected at their upper ends by an inverted-U channel 12. I will describe the construction at one end of the bridge only, it being understood that the whole construction is duplicated at the other end. One of the posts 11 or a continuation of it in the 70 form of a pipe 13 extends down in the abutment 7 to a point below the bottom of the river 14, where it is connected by an elbow 15 to a horizontal pipe 16, extending underneath the river 14 to a point near the center pier 6. 75 The pipe 16 near the pier 6 is connected by means of an elbow 17 to the lower end of a pipe 18, which extends up substantially vertically to about the top of the pier 6. 80 The opposing sides of the posts 11 are provided with vertical guides 19, between which the gate or door 20 is arranged to freely slide. To reduce the amount of power required to operate the gate 20, a counterweight 21 is preferably arranged to travel in one post 11, 85 being connected through a cable 22 to the upper end of the gate 20 at 23. The cable 22 is double a portion of the distance and passes over the sheaves 24, which are pivoted in the channel 12. Another cable 25 is secured to 90 the top end of the gate 20 at 23 and passes over the sheaves 26, pivoted in the channel 12. Thence the cable 25 extends down the hollow post 11 and pipe 13 around the sheave 27 in the elbow 15, through the pipe 16, 95 around the sheave 28 in the elbow 17, thence up through the pipe 18, over the sheave 29, pivoted to a bracket secured to the top of the pier 6, and finally to a point on the bridge 5 slightly beyond the center, where its end is 100 secured in a hole by means of a wedge 30. The posts 11 are of sufficient height above the roadway to allow the gate 20 to be raised to a height so its lower end will be above the highest vehicle intended to cross the bridge. 105

In Fig. 1 the full lines indicate the closed position of the bridge, and the dotted lines indicate the open position of the bridge. The connection of the end of the cable 25 to the bridge 5 is such that when the bridge is closed the gates are open and when the bridge is open the gates are closed. The weight of

the gate 20 is such as to overcome the combined weight of the counterweight 21 and cable 25, so that the cable 25 is always held taut.

- 5 In operation if the bridge 5 is turned from the closed or full-line position, as viewed in Fig. 1, to the open or dotted-line position the gates will both move downward simultaneously with the turning of the bridge, because 10 the ends of the cables 25 which are secured to the bridge will be moved by the bridge toward the sheaves 29.

If from constant use either one or both the cables 25 should become stretched, they can 15 readily be adjusted to the proper position by withdrawing the wedge 30 when the bridge is open, pulling up all the slack, and then replacing the wedge 30 again.

Having thus fully described my invention, 20 what I claim as new, and desire to secure by Letters Patent of the United States, is—

1. In a bridge-gate, a gate arranged to travel a determined distance vertically, a bridge arranged to turn on a pivot a deter-

mined distance, and a cable having one end rigidly connected to said gate and its remaining end rigidly connected to said bridge at such distance from its pivot that the complete movement of the bridge will cause a complete movement of said gate. 25

2. In a bridge-gate, a gate arranged to travel in vertical ways, a bridge arranged to be opened and closed and a cable having one end rigidly secured to said gate and one end adjustably secured to said bridge by a wedge 30 driven into a hole to clamp said cable, whereby the gravitating force of said gate is constantly exerted against said bridge and the gate and bridge are moved simultaneously. 35

In testimony whereof I have signed my name to this specification, in presence of two subscribing witnesses, this 18th day of November, 1904, at Chicago, Illinois.

JOHN FOWLER.
